UNITED STATES PATENT OFFICE.

JOHN T. AUSTIN, OF HARTFORD, CONNECTICUT, ASSIGNOR TO AUSTIN ORGAN COMPANY, OF HARTFORD, CONNECTICUT, A CORPORATION OF MAINE.

SHUTTER-OPERATING MECHANISM FOR PIPE-ORGANS.

1,090,963.

Specification of Letters Patent. Patented Mar. 24, 1914.

Application filed May 27, 1913. Serial No. 770,206.

To all whom it may concern:

Be it known that I, JOHN T. AUSTIN, a citizen of the United States, residing at Hartford, in the county of Hartford and State of Connecticut, have invented certain new and useful Improvements in Shutter-Operating Mechanism for Pipe-Organs, of which the following is a specification.

This invention relates to shutter-operating mechanism for pipe-organs, the object of the invention being to provide means of this character which is simple and compact in construction, positive and certain in action, and by which rapidity of operation of the shutter or shutters is insured.

In the drawings accompanying and forming part of the present specification, I have shown in detail one of the several convenient forms of embodiment of the invention which to enable those skilled in the art to practice the same, will be fully set forth in the following description. I do not restrict myself to this showing; I may depart therefrom in several respects within the scope of the invention defined by the claims following said description.

Referring to said drawings: Figure 1 is a side elevation of shutter-operating mechanism involving my invention, one side of the pressure-box being removed, any part of the top and a purse being in section. Fig. 2 is a cross section on the lines 2—2 of Figs. 1 and 3. Fig. 3 is a top plan view of the bellows-controlling pneumatics, a portion of the bellows, the magnets associated therewith and certain coöperating devices. Fig. 4 is a transverse section on the line 4—4 of Fig. 3. Fig. 5 is a similar view, the section being on the line 5—5 of Fig. 3. Fig. 6 is a sectional diagram showing circuit connections, the section being on the line 5—5 of said Fig. 3. Figs. 7 and 8 are sectional side elevations of pedal mechanism the parts being in different positions. Fig. 9 is a horizontal section on the line 9—9 of Fig. 7.

Like characters refer to like parts throughout the several figures of the drawings which it will be seen are on different scales.

In certain kinds of organs there is provided shutter mechanism (consisting of one or more shutters) which is opened to secure what is known as a "swell", and the purpose of the operating mechanism is to effect the action of said shutter mechanism. Said

operating mechanism can be employed for moving the shutter mechanism in either direction, although I prefer that it be utilized for closing the same, said shutter mechanism being openable by a weight or springs. Although I show said operating mechanism as being actuated by pressure, this is not essential, as the results can be obtained by exhaust.

When pressure is employed, certain of the operative parts are inclosed in a pressure-box as 2 into which compressed-air is directed by means of a suitable pump as common in this art. This pressure box incloses a bellows as 3 comprising the sections 4, 5, 6, 7, 8 and 9, of progressively increasing capacity and in communication by means of ducts hereinafter described with the passages 10, 11, 12, 13, 14 and 15 respectively formed in the bottom 16 of the pressure-box 2 and extending longitudinally thereof. (See for example Figs. 2, 3 and 5). Each of the passages 10 to 15 inclusive is adapted to be alternately connected with the interior of the pressure box 2 and with the atmosphere and any suitable means may be provided for effecting such results; for instance the means shown and now to be described may be employed. Below the several passages 10 to 15 inclusive, is a longitudinally-extending chamber or space 17 connected by the port 18 (Fig. 5) with the atmosphere. Connecting each of these passages with the chamber 17 is a port 19, while connecting said passages with the interior of the pressure box 2 is a port 20 each port being controlled by a valve, the valves for the ports 19 being designated by 21, while those for the ports 20 are denoted by 22, said pairs of valves 21 and 22 as illustrated being rigidly carried by stems 23 which project through the respective pairs of ports. In Fig. 5 the bellows section 9 is shown as expanded or distended, the same statement applying to the bellows section 8, although the other bellows sections 4, 5, 6 and 7 are contracted. It will be seen in this view that the valve 21 co-operative with said section 8, covers its port 19 while the corresponding valve 22 uncovers its port 20 thus putting the bellows section 8 into communication with the interior of the pressure-box 2 to cause the expansion of said bellows section 8. It will be evident that if said valve 22 be closed or moved against its seat upon the under side

100

110

of the port 20 and that if said valve 21 be opened the bellows section 8 will be put into communication with the atmosphere by way of the passage 14, port 19, chamber 17 and port 18, so that said section 8 can be collapsed by the pressure of air in the pressure box 2. When the bellows section 9 is cut off from communication with the interior of the pressure box and put into communication with the atmosphere, it will be similarly contracted. The means shown for operating the pairs of valves 21 and 22 will be hereinafter described.

It is not broadly new with me to provide a bellows for effecting the action of shutter mechanism; I am acquainted with a bellows construction for the same purpose. In the old organization, the ducts by which air is led into or from the bellows section, are disposed exteriorly of the bellows, which makes a quite complex construction. One of the broader features of the present invention consists in locating these ducts within the bellows, by virtue of which compactness is secured without affecting in any wise the efficiency of the bellows. It will, therefore, be clear that the bellows can be of any suitable character so long as the ducts are disposed within the same, and these ducts can be either utilized for exhausting the sections or for supplying air thereto, the manner in which the bellows is collapsed or contracted being immaterial. I secure the best results by employing bellows, the sections of which swing and therefore prefer to use this type of bellows as thereby I can dispose the ducts, which ordinarily extend from the bottom toward the top of the bellows, adjacent or in proximity to the centers of motion of the swinging sections of the bellows, thus providing for a relatively small amount of collapse or flexure of said ducts or tubes which would not be the case were the same remote or some distance from said centers of motion. The bellows 3 comprises in its make-up the stationary bottom 105, (fastened to the bottom of the box 2) the swinging top or leaf 106 and the five interior swinging members or leaves 107, 108, 109, 110 and 111. Between these leaves and also between the leaf 107 and the bottom 105 are the spacing strips 112 triangular in cross section and the butts of the leaves and the spacing strips are cemented to the rear wall of the bellows, by reason of which the leaves are hinged and can swing as the bellows expands and contracts. The bottom or base 105 and leaf 107 present the bottom and top of the lower bellows section 4, the leaves 107 and 108 presenting the bottom and top of the bellows section 5, the leaves 108 and 109 presenting the bottom and top of the bellows section 6, the leaves 109 and 110 constituting the bottom and top of the bellows section 7, the leaf 110 and leaf 111 presenting

the bottom and top of the bellows section 8, while the leaves 111 and 106 present the bottom and top of the bellows section 9. All the bellows sections except the lowermost one (4) are connected by flexible tubes (for example of leather) with the passages cooperative therewith, the duct 113 connecting the bellows section 4 directly with its appropriate passage. Rising from the remainder of the passages and fastened with in openings in the bottom leaves of the bellows sections 5, 6, 7, 8 and 9 are tubes 114, 115, 116, 117 and 118 respectively, the lower ends of these tubes being fastened in openings 119 intersecting the passages 11 to 15 cooperative with the bellows sections 5 to 9 inclusive. The duct 113 to which I have already referred connects with its passage 10 by a port 120. It will, therefore, be clear that the interior of each bellows section is at all times, in communication with a co-operating passage.

The bellows 3 can be connected with the shutter mechanism in any desirable manner, for example by the means shown and now to be described. In the top of the pressure chamber 2 is an opening 21 in which is rigidly fitted the lower enlarged end of the purse 25, the link 26 pivoted at its lower end to an eye 27 connected with the top of the bellows 3 being inclosed by said purse 25 and extending through the upper end thereof, the connection 28 being joined to the eye 29 at the upper end of said link 26. The upper reduced end of the purse 25 is wrapped closely or in an airtight manner around the shank of the link 26 just below the eye 29. As will be understood the bellows 3 can be collapsed in stages, six in the present case, although the number is not a matter of consequence. The first stage of collapse is secured by the exhaustion of the bellows chamber 9, the second stage by the exhaustion of the bellows chamber 8, and so on, and each time a compartment or section of the bellows is exhausted, the bellows is collapsed thereby drawing down the link 26 and through the connection 28 causing closing of the shutter mechanism, the maximum closure of the shutter mechanism being accomplished when all sections of the bellows are collapsed. By successively putting sections or compartments of the bellows 3 into communication with the interior of the pressure chamber 2, as by opening any one or more of the valves 22, the bellows 3 will be expanded to effect the opening of the shutter mechanism, the bellows being shown as fully expanded in Fig. 1. The extent to which the several sections may be expanded progressively increases from the minimum range of section 4 to the maximum range of section 9.

Governing each pair of valves (21 and 22) is a pneumatic, there being six of such

pneumatics (Fig. 3) denoted by 30, 31, 32, 33, 34 and 35 respectively each being adapted as shown for alternate connection with the interior of the pressure box 2 and the atmosphere, although they are normally as will hereinafter appear in communication with the interior of the pressure box. The pneumatics are shown as being of bellows type, the bottom of the pressure box having 10 angular passages denoted by 36 in communication with the respective pneumatics or bellows 34. The passages 36 intersect the ports 37 respectively opening at their upper ends into the interior of the pressure box 2 and at their lower ends into the transverse passage 38 connected by the ports or openings 39 with the chamber 17 to which I have already referred and which it will be remembered is in uninterrupted communication with the atmosphere by way of the port or opening 18. Cooperative with each port 37 is a pair of valves as 40 and 41, the valves 40 being rigid with the stems 42 (Fig. 5) while the valves 41 are loose on said stems 25 and cooperative with collars 43 rigid therewith. Each valve 40 controls the lower end of a port 37 while the upper valves 41 control the upper ends of said ports. In Fig. 5 the valve 40 is shown as closing the port 37, the valve 41 being open, so that the pneumatic 34 is in communication with the interior of the pressure box 2, by reason of which it can be held expanded to thereby maintain the valve 21 closed and the valve 35 22 open as already explained to put the bellows section or compartment 8 in communication with the interior of the pressure box. If the valve 41 be closed against its seat at the upper end of the port 37 during which 40 it falls away from the collar 43, the valve 40 will be caused to open so as to put the pneumatic 34 (Fig. 5) into communication with the atmosphere by way of the passage 36, port 37, transverse passage 38, port 39, chamber 17 and port 18 whereby the compressed air in the pressure box 2 will cause the bellows 34 to collapse and through suitable connections, to effect the closing of the valve 22 and the simultaneous opening of 45 the valve 21. Fastened to the upper boards of the respective pneumatics or bellows 30 to 35 inclusive are strips as 44 perforated to receive the upper ends of the valve stems 23 between collars 45 thereon. It follows therefore that when the bellows or pneumatic 34 is collapsed in the manner already described, the stem 23 of the valve mechanism connected with said bellows 34 is elevated through the agency of the strips 44 to close the valve 22 and simultaneously open the valve 21 to put the compartment or bellows section 8 into communication with the atmosphere as already set forth to secure the collapse of the said bellows section and a partial collapse of the bellows 3 as a whole and a cor-

responding amount of movement of shutter mechanism.

Mounted on the inner side of the wall 46 of the pressure chamber or case 2, are the valve-operating pneumatics 47, 48, 49, 50, 51 and 52 which as will be understood correspond in number with the sections or compartments of the bellows 3, there being ports or passages 53 in said wall, opening at their inner ends into the respective pneumatics 47 to 52 inclusive. The valves 41 are connected with the substantially-horizontal arms of the elbow or angle levers 54, the approximately vertical arms of said levers being connected with the inner or movable leaves of the pneumatics 47 to 52 inclusive, said levers being fulcrumed at their elbows to a strip 55 fastened by screws or otherwise to the upper surface of the bottom of the pressure chamber 2 interiorly thereof. The ports 53 to which I have referred are closed at their upper ends by caps 56 and between their ends, branch ports 57 and 58 lead oppositely therefrom, the port 58 consisting of the opening through the sleeve 59. (Figs. 5 and 6). The ports 57 open into the chamber 60 connected by the passage 61 with the passage 38 to which I have already referred and which it will be remembered has uninterrupted communication with the atmosphere. Controlling the ports 57 are the valves 62, while the diaphragm valves 63 control the ports 58, the valves 62 and 63 in pairs being carried by stems 64. The diaphragm valves 63 are held marginally by 100 the wall 46 and strip 65 fastened interiorly to said wall, there being a space or opening 66 between each diaphragm valve 63 and the adjacent wall 46 for a purpose that will hereinafter be set forth, the spaces or openings 66 being in direct communication with the interior of the pressure chamber 2. The diaphragm valves 63 are disposed opposite the pockets or cavities 67, the ports 68 opening into the respective pockets 67. Fitted 110 in the strip 65 are tubular valve seat members 69 with which are cooperative the valves 70 of disk type normally held closed by compressed air passing through perforations 71 in the strip 72 fastened to the strip 115 65. The air in the pressure box normally holds these valves 70 closed against the tubes 69 and also acts against the diaphragm valves 63 to hold the same closed against the ports 58 as illustrated in Fig. 6.

The interiors of the valve seat members 69 are connected with the passage 73 which opens into the passage 74 (Fig. 4) which in turn is connected by a passage 75 with the chamber 60 which it will be remembered is 125 in communication with the atmosphere. It will be assumed that a valve 70 is operated to move it away from the cooperating tubular member 69 and to cover a pair of adjacent perforations or ports 71. In this event 130

the pocket 67 is put into connection with the atmosphere by way of the passage 68, tube 69, passage 73, passage 74, passage 75, chamber 60, passage 51, passage 38, ports 39, 5 chamber 17 and port 18, the pressure of air being relieved on the left side of said diaphragm valve 63, so that the compressed air passing through the space 66 can act against the right side of said diaphragm valve and 10 cause it to uncover the port 66 and at the same time cause the valve 62 to cover the port 57 and to put the passage 53 connected therewith into communication with the interior of the pressure chamber 2, so that 15 compressed air from said passage 53 can flow into the appropriate pneumatic (any one of those numbered 47 to 52 inclusive) to expand said pneumatic and thereby cause the same to effect the closing of the valve 41 20 and the opening of the valve 40 and necessarily the putting of the coöperating channel 36 into connection with the atmosphere so as to permit of the collapse of the proper pneumatic (one of those numbered 30 to 35 25 inclusive) by the pressure in the pressure box 2. When said pneumatic (30 to 35) is collapsed the valve 22 and the valve 21 connected therewith are operated, the valve 22 to close its port 20 and the valve 21 to 30 cover its port 19 so that the corresponding bellows section is put into communication with the atmosphere and can be collapsed by the air in the pressure box 2 as already set forth.

35 In the present case the valves 70 are electrically operated to cause the contraction of the bellows 3 and the means shown for this purpose may vary but as shown comprises the horseshoe magnets 76 (six in number) 40 the branches or poles of which extend through openings in the strip 72 and are opposite the corresponding valves 70 (Figs. 5 and 6), said valves constituting armatures for said magnets. A generator such as an 45 electric battery is shown at 77, the conductor 78 (Fig. 6) leading from one terminal of said battery and being connected with the contact spring 79, the conductor 80 leading from the other terminal of the battery 50 and having branches 81 extending therefrom and connected with one leg of each of the magnets 76, the other legs of the magnets being connected by branch wires 82 with the contact springs 83, 84, 85, 86, 87 55 and 88, which are set between their ends as is the spring 79, in notches in the wooden strip 89 fastened as by screws to the web 90 (Figs. 7 and 8) of the pedal mechanism hereinafter more particularly described. 60 The circuit controller 91 is connected with the pedal, and it has a permanent electrical connection with the strip 79 for instance by being slidable through a perforation therein, the bowed or U-shaped lower end 92 65 of the circuit controller 91 having a guide

connection with the extension 93 at the lower end of the strip 89. In Fig. 7 the shorter branch of the U-shaped portion 92 of the circuit controller or switch 91 is shown as being out of contact with all of 70 the six strips 83 to 88 inclusive, in view of which none of the magnets 76 will be energized. It will be clear that if the circuit controller 92 be elevated (as will herein-after appear by the depression of the pedal 75 with which said circuit controller is connected) the strips 83 to 88 will be successively engaged by the circuit controller 92 to close the local circuits, the energization of the magnets 76 and the collapse of the 80 compartments of the bellows 3 in succession.

Pivotedly supported between its ends by the web 90 is the pedal 94 to which the circuit controlling member or switch 91 is pivotally connected (Figs. 7 and 8) so that on 85 the depression of the pedal from the position shown in Fig. 7 to that shown in Fig. 8 the circuit controlling member 91 will be lifted to close successively the local circuits of the several magnets 76. Depending from 90 the toe portion of the pedal 94 is the fin 95 adapted to be embraced by the pads 96 set in a fork 97 at the rear of the web 90, the branches of the fork 97 being perforated to receive the substantially circular members 98 pressed toward each other by the bowed spring 99, the free ends of which enter countersinks 100 in the outer faces of the two members 98 to thus frictionally hold the pedal 94 in any position to which it may 100 be moved.

It is immaterial in what order the sections of the bellows are expanded or contracted. It will be assumed that they are expanded commencing with the lowermost 105 section. In this event they inaugurate their contraction commencing with the uppermost section.

What I claim is:

1. A bellows in sections, and ducts inclosed by the bellows and in communication with the interiors of the respective sections thereof.

2. A bellows in sections, a pressure box inclosing said bellows, ducts inclosed by the 115 bellows and in communication with the interiors of the respective sections thereof, and mechanism operable at will, for putting said ducts into communication with the interior of the pressure box or with the atmosphere.

3. A bellows in sections comprising hinged leaves, and ducts within the bellows, in communication with the interiors of sections thereof and in proximity to the hinges of the 125 leaves.

4. A bellows in sections, and flexible ducts inclosed by the bellows and in communication with sections thereof.

5. A bellows in sections comprising hinged 130

leaves, and ducts within and extending from the bottom toward the top of the bellows adjacent the centers of motion of said leaves, the ducts being in communication with the interiors of sections of the bellows.

6. A bellows in sections, certain of the sections being provided with swinging bottom leaves having openings, and ducts enclosed by the bellows, a duct being fitted in each opening.

7. A shutter-operating bellows in sections, means for causing the successive action of the sections of the bellows, said means including a plurality of magnets corresponding in number and coöperative with said bellows sections, each magnet being in a branch circuit, and a movably mounted member provided with means for successively closing said circuits.

20 8. A shutter-operating bellows in sections, means for causing the successive action of the sections of the bellows, said means in-

cluding a plurality of magnets corresponding in number and coöperative with said bellows sections, each magnet being in a branch circuit, and a pedal provided with means for successively closing said circuits.

9. A shutter-operating bellows in sections, means for causing the successive action of the sections of the bellows, said means including a plurality of magnets corresponding in number and coöperative with the respective bellows sections, each magnet being in a branch circuit, a movably mounted member provided with means for successively closing said circuits, and means for holding said member in a position to which it may have been moved.

In testimony whereof I affix my signature in presence of two witnesses.

JOHN T. AUSTIN.
